UNITED STATES PATENT OFFICE.

JOHN FARKAS, OF DETROIT, MICHIGAN.

THERMOSTATIC CONTROL FOR CARBURETORS.

Application filed March 13, 1922. Serial No. 543,173.

The invention relates to thermostatic control devices for carburetors and refers particularly to a thermostatic control device subjected to heat radiated from an exhaust manifold of an engine and adapted to be operatively connected to the needle valve of a carburetor. One of the objects of the invention is to provide a thermostatic needle valve which can be easily inclosed within a housing at the side of the exhaust manifold so that no portion of the thermostatic bar will be exposed to the air passing the lower end of the housing, which will rotate the carburetor needle valve a sufficient distance, which does not vary in operation and which is strong and yet requires no more material than other forms of thermostatic bars. With the above objects in view, the invention resides in the novel features of construction as more fully hereinafter set forth.

In the drawings:

Figure 1 is a perspective view showing a portion of an engine with my thermostatic control device applied;

Figure 2 is a side elevation of the device showing the same applied to the exhaust manifold;

Figure 3 is a cross section on the line 3—3 of Figure 2.

1 and 2 are respectively the exhaust and intake manifolds of an internal combustion engine, and 3 is a carburetor secured to the intake manifold.

4 is the housing of my thermostatic control device having the side walls 5 abutting the exhaust manifold 1, the front wall 6 connecting the side walls and the upper wall 7 extending between the upper ends of the side walls as well as the front wall. The lower end of this housing is open. 8 is a bracket secured to the lower end of the front wall 6 and extending downwardly a sufficient distance to be clamped between the clip 9 and the rear bifurcation of the intake manifold 2, this bracket supporting the housing. 10 is a spiral thermostatic coil extending transversely of the housing near its middle and having one end fixedly secured to the front wall 6 of the housing and the other end fixedly secured to the upper end of the rod 11 extending upwardly within the housing 4. 12 is a yoke secured to the lower end of the rod 11 and having its arms engaging in apertures in the transversely extending plate 13 at the upper end of

the needle valve 14 of the carburetor, this needle valve controlling the flow of gasoline. The yoke 12 is adjustably secured to the rod 11 so as to permit various positions of rotative adjustment relative thereto, as by means of the sleeve 15 fixedly secured to the rod and the set screw 16 threaded in the sleeve and abutting the yoke, whereby the rotative position of the needle valve 14 of the carburetor may be varied independently of the spiral thermostatic element.

With the spiral construction of thermostatic bar, the thermostatic coil can be easily inclosed within its housing at a distance sufficiently above its open lower end so that it will not be exposed to air passing the lower open end of the housing. Also the thermostatic coil is of strong construction, can be easily manufactured, and requires no more material than other and weaker forms of thermostatic coils, and at the same time it will have sufficient movement to rotate the needle valve 14 of the carburetor the necessary angular distance. Furthermore, with this construction of thermostatic bar and the manner of housing the same, the operation of the device varies but slightly.

What I claim as my invention is:

1. In an internal combustion engine, the combination with a carburetor having a rotatably adjustable needle valve and an exhaust manifold above said carburetor, of a housing adjacent to said manifold and arranged at one side thereof, said housing being closed at the front top and sides and being open at the rear, a spiral thermostatic element within said housing exposed to direct radiation from said exhaust manifold and having one end secured to said housing, a rod rotatable about its axis and extending substantially vertical at the side of said exhaust manifold, said rod having one end thereof engaging and directly secured to the opposite end of said thermostatic element and a yoke adjustably secured to the opposite end of said rod so as to permit various positions of rotative adjustment relative thereto and connected to said valve for adjusting the same upon movement of said thermostatic element.

2. In an internal combustion engine, the combination with a carburetor having a rotatably adjustable needle valve and an exhaust manifold above said carburetor, of a housing adjacent to said manifold and at

ranged at one side thereof, a spiral thermostatic element within said housing having one end secured thereto, a rod rotatable about its axis and extending substantially vertically at the side of said exhaust manifold, said rod having one end thereof secured to the opposite end of said thermostatic element and a yoke adjustably se-

cured to the opposite end of said rod so as to permit various positions of rotative adjustment relative thereto and connected to said valve for adjusting the same upon movement of said thermostatic element.

In testimony whereof I affix my signature.

JOHN FARKAS.
